UNITED STATES PATENT OFFICE.

ALBERT B. HERRICK, OF CLEVELAND, OHIO, ASSIGNOR TO MATIE C. MESSLER, OF PAWTUCKET, RHODE ISLAND.

GENERATING MECHANISM.

1,200,120.

Specification of Letters Patent.

Patented Jan. 7, 1919.

Original application filed November 29, 1912, Serial No. 733,976. Divided and this application filed November 27, 1915. Serial No. 63,860.

To all whom it may concern:

Be it known that I, ALBERT B. HERRICK, a citizen of the United States, and a resident of Cleveland, county of Cuyahoga, and State of Ohio, have invented a new and useful Improvement in Generating Mechanism, of which the following is a specification, the principle of the invention being herein explained and the best mode in which 10 I have contemplated applying that principle, so as to distinguish it from other inventions.

The subject of the present invention is mechanism for generating an electro-motive force, such mechanism being adapted particularly for use in an igniter which will be attached to an engine cylinder in the position usually taken by the spark plug, the compression of the engine being used to 20 furnish the power necessary to perform the movements required in the generating mechanism; in other words, the generating mechanism is a self contained magneto adapted to be automatically operated by the compression of the gases in the cylinder of an internal combustion engine, although it will be understood that other uses for the mechanism will readily suggest themselves.

The present application relates to the induction mechanism described in my co-pending application, Serial No. 733,976, filed November 29, 1912, now issued into United States Patent No. 1,174,145, dated March 7, 1916, from which the present application 35 is divided.

In said annexed drawing:—

Figure 1 is a central vertical section through one form of my invention; Fig. 2 is a section on the line 2—2, in Fig. 1; Fig. 40 3 is a view in perspective of the armature and the contact members attached to the ends of the magnet; Figs. 4 and 5 are end elevations of the mechanism showing the armature in its upper and lower position; Fig. 45 6 is a diagram showing the method of wiring the device; Fig. 7 is a side elevation of a modified form of my invention; Fig. 8 is a view similar to Fig. 7, but showing the armature in its raised position; Figs. 9 and 50 10 are views corresponding to Figs. 7 and 8, showing a third form of the invention, and Fig. 11 is a section on the line 11—11, in Fig. 1.

In the construction shown in Fig. 1, I at-

55 tach to a hollow spark plug 1 a brass plate or base member 2 upon which will be mounted the contacts 3 and 4 attached to the ends of a magnet 5. The magnet is preferably laminated or sectional, as shown in Figs. 1 and 2. Upon the top of the members 3 and 4, I attach a second brass plate 6 upon which there is mounted a lubricating cup 7, the construction of which need not be explained in detail.

56 The magnets 5 are preferably of U-shape and extend horizontally around an armature 8, consisting preferably of a primary coil 9 only, and a soft iron core 10. The armature is provided at its top and bottom with plates 11 and 12 attached to the core. 60 To the bottom plate 12 is attached a piston member 13 slidably mounted in the hollow chamber formed in the spark plug and adapted to be operated by the compression in the engine cylinder. The piston will be 65 lubricated from the oil cup by suitable mechanism. Attached to the piston 13 are a spring arm 14 terminating in a contact 15 and a rod 16 terminating in a contact 17, adapted to normally engage the contact 15, 70 thus forming a closed circuit, as both contact members are suitably connected to the armature, the connection being illustrated in Fig. 6. The spring arm 14 extends around the contact 15 and engages a collar 18 slidably 75 mounted upon a rod 19 extending downwardly from the end of the spark plug. The end of the rod 19 is threaded and is engaged by a stop in the form of a nut 20. The spring arm 14 is engaged between the 80 collar 18 and the nut 20, a spring 21 normally retaining the collar 18 in its lower position against the nut 20.

85 The magnets may be suitably inclosed in a casing (not shown) which will preferably be attached to the members 2 and 5 forming the bottom and top plates respectively of the device. A sleeve 22 is suitably attached to the top and bottom plates and extends vertically between the same inclosing a rod 23 provided with a handle 24 and attached at its lower end by means of a pin 25 to a lever 26 which is pivoted intermediate its ends about a pin 27 mounted in an extension of the bottom member 2. The 90 lever 26 terminates in a yoke 45, each arm of the yoke engaging a pin 28 which is slidably mounted at the bottom of the arma-

ture. An adjusting member 29, in the form of a set screw, is mounted in the top 5 and is adapted to bear against a spring 30 also, attached to the top member 5, and adapted to bear against the plate 11 on the top of the armature. The action of the spring 30 tends to retain the armature in its lower position, shown in Fig. 1, until the armature is raised by means of the piston 13 operated by the compression in the cylinder, or until the handle 24 is pushed downward, thus oscillating the lever 26 and operating the armature upward through the pins 28.

The core 10 is formed at either end with contact members 32 and 33 which lie in parallel planes, and are directed in oblique directions, thus forming substantially a letter X. The contact members 3 and 4 on the ends of the magnets are formed with complementary contacts 35, 36, 37 and 38, which are adapted to be engaged by the contacts 32 and 33 in the various positions of the armature. In the normal position of the armature, shown in Fig. 4, the face 39 of the contact 32 engages the face 37 of the contact 4; also the lower face 40 of the contact 33 engages the face 36 of the contact 3. The magnetic circuit is then closed, the flux being from the north pole of the magnet through the armature in the direction indicated by the arrow in Fig. 4, and returned to the south pole of the magnet. Upon the operation of the armature into its upper position, the contact face 41 of the contact 32 engages the face 35 of the contact 3, while the contact face 33 engages the contact face 37 on the member 4. The direction of the magnetic flux is therefore reversed, the direction now being shown by the arrows in Fig. 5. In this way a very considerable electrical current can be induced, as the current fluctuates from a positive maximum, which is the current induced in the coil, as the armature is moved into its normal position, to a negative maximum, which is the current induced in the coil as the armature is moved into its raised position shown in Fig. 5. As the armature is raised, however, the rod 16 is also raised, as well as the spring arm 14. The spring 14 will normally be slightly stronger than the spring 21, so that the contact 15 will remain in engagement with the contact 17 during the first portion of the upward movement of the coil. As soon, however, as the spring 21 is compressed, the rigidity of the same is increased and it becomes stronger than the spring 14. At this point, therefore, the spring arm 15 and consequently the contact 15 will begin to lag and a sharp break will be produced between the contacts 15 and 17, thus producing a spark between the terminals of the plug. If it is desired to produce a spark when the engine is not running, it is only necessary to depress the handle 24, thus giving

the same upward movement to the armature as is produced by the compression in the engine cylinder. A current is therefore induced in the armature coil and the operation is exactly as has been described above, the same spark being produced at the terminals of the plug.

In the present mechanism it is unnecessary to use a high tension secondary coil, and I have therefore shown the armature as consisting only of a primary coil and a soft iron core. The device shown in Figs. 1 to 6 inclusive, is adapted to operate as a low tension ignition device, in which type of system the circuit is broken in the cylinder, in which case a high tension current is not required to bridge the gap between the spark plug terminals. If desired, however, the mechanism may be used for high tension ignition, in which case a high tension secondary coil will be required.

In Figs. 7 to 10 inclusive, I show alternative forms of construction designed to be used as high tension ignition devices. In Fig. 7 I show a spark plug 50 which is hollowed out to form a chamber 51 in which there will operate a piston 52. The piston 52 is attached to an armature 53 having a coil and a soft iron core, preferably laminated, the armature having contact pieces or teeth 54 and 55 formed at either end of the same. A magnet 56 is provided, extending around the armature and being provided with contacts or polar faces 57, 58, 59 and 60, adapted to be magnetically engaged by the teeth on the armature when the same is operated. The magnet is suitably attached to a base plate 61 attached to the spark plug 50. The terminals of the spark plugs 62 and 63 are attached, one to the spark plug proper and one to the coil, the latter being extended through a tube 64 about which the piston slides. The terminals are therefore maintained at a predetermined distance from each other, which distance is not varied by the action of the armature. In the lower position of the armature the teeth 54 and 55 on the core of the coil are in engagement with the faces 57 and 60 of the magnet, respectively. Assuming that the poles of the magnet are as represented by the letters N and S in Figs. 7 and 8, the magnetic flux will then pass from the face 57 to the tooth 54 on the core, through the core and back to the magnet through the tooth 55 and face 60. When the armature is raised into the position shown in Fig. 8, the magnetic flux passes from the face 59 to the tooth 55, upwardly through the core and back to the magnet through the tooth 54 and face 58, thus reversing the direction of the flux. The reversing of the direction of the magnetic flux induces a current which is passed through the plug terminals by suitable mechanism. Suitable mechanism for this

purpose may be similar to that described in my co-pending application, Serial No. 700,594, filed May 31, 1912, now issued into United States Patent No. 1,177,701, dated

5 April 4, 1916, or may be of the construction shown in Figs. 1 and 2.

In Figs. 9 and 10, I show a third form of the invention in which the arrangement of the teeth on the core and the polar faces on 10 the magnet differ from that shown in the two previous forms. In this form I also show my preferred form of piston member and hollow chamber in the spark plug. The form of the polar faces and the teeth is substantially like that shown in Figs. 7 and 8, except that the magnet is cut away to form the polar faces 90, 91, 92 and 93, which are adapted to be engaged by the projecting teeth 94, 95, 96 and 97 on the core. The direction of the magnetic flux will be reversed by the operation of the armature, the direction of the flux being shown by the arrows in Figs. 9 and 10. The spark plug is hollowed out to form an enlarged chamber 100 which 15 is provided with a beveled shoulder 101 at its upper end and an oppositely beveled shoulder 102 at its lower end. The piston is provided with a complementary beveled portion 103 adapted, when the piston is raised, 20 to contact the shoulder 101, thus providing a secure closure of the aperture in the spark plug and preventing the entrance of any of the hot burning gases into the space surrounding the armature and the magnets. In 25 this way the life of the magnets and the armature is increased, as the action of the hot gases upon the same tends to break down the insulation and to de-magnetize the magnets.

30 40 The present invention provides an automatically operated generating mechanism in which the coil is reciprocated to cause the establishment of a current therein, which is secured by the arrangement of the magnet 45 and the contacts on the magnet and core, the arrangement being such as to cause a reversal of the magnetic flux through the coil.

45 The travel of the coil is slight and the improved type of piston and chamber prevent 50 the escape of any gas from the engine cylinder.

Other modes of applying the principle of my invention may be employed instead of the one explained, change being made as

regards the mechanism herein disclosed, provided the means stated by any of the following claims or the equivalent of such stated means be employed.

I therefore particularly point out and distinctly claim as my invention:—

1. In a generator, the combination of a permanent field magnet having spaced contacts thereon, a reciprocably mounted armature having complementary spaced contacts, and means for reciprocating said armature to change the engagement of said contacts and reverse the direction of flux through said coil.

2. In a generator, the combination of a permanent field magnet having spaced contacts thereon, a reciprocably mounted armature having complementary spaced contacts, adapted to engage with said contacts on said magnets, reciprocation of said armature being adapted to change the contacts in engagement to reverse the direction of flux through said armature, and means for reciprocating said armature.

3. In a generator, the combination of a permanent field magnet having its poles adjacent one another, two spaced contacts formed on each such pole of said magnet, an armature reciprocably mounted between such poles, complementary spaced contacts mounted on said armature, reciprocation of said armature being adapted to change the contacts in engagement to reverse the direction of flux through said armature, and means for reciprocating said armature.

4. In a generator, the combination of a permanent field magnet having its poles adjacent one another, two spaced contacts formed on each such pole of said magnet, an armature reciprocably mounted between such poles, complementary spaced contacts mounted on said armature, reciprocation of said magnet being adapted to change the contacts in engagement to reverse the direction of flux through said armature, and means for reciprocating said armature.

Signed by me this 23 day of November 1915.

ALBERT B. HERRICK.
